The ornamental design for a disc brake shim, as shown and described.

DESCRIPTION

FIG. 1 is a front elevational view of a disc brake shim showing our new design;

FIG. 2 is a front elevational view thereof; the rear being a mirror image of the view shown;

FIG. 3 is a top plan view thereof;

FIG 4 is a bottom plan view thereof; and,

FIG. 5 is a side view thereof, the opposite side being a mirror image of the side shown.
